UNITED STATES PATENT OFFICE.

FRANK GROCH, OF COBALT, ONTARIO, CANADA.

ORE CONCENTRATOR.

1,413,724.

Specification of Letters Patent. Patented Apr. 25, 1922.

Original application filed July 3, 1916, Serial No. 107,434. Divided and this application filed July 29, 1918. Serial No. 247,155.

To all whom it may concern:

Be it known that I, FRANK GROCH, a citizen of the United States, residing in Cobalt, in the Province of Ontario and Dominion 5 of Canada, have invented certain new and useful Improvements in Ore Concentrators, of which the following is a specification.

This invention relates to ore concentration in which the metals and metalloids in 10 an ore-pulp containing them are separated from the gangue by the selective action of a froth or foam producing agent, such as oil, which carries the metallic particles to the surface of a bath while the particles of 15 gangue are allowed to settle. By thus separating the values from the gangue the two products may be separately removed and further treated.

The object of my invention is to provide 20 improved apparatus for practicing a method of concentration of the kind referred to.

In such processes it is important that the metalliferous particles should be detached or 25 separated from the particles of gangue as thoroughly as possible in order that the buoyant oil or other froth producing substance and the upward currents of air may cause them to rise while the gangue is settling and it is also important that, where 30 possible, the process of separation should be continuous in a single apparatus and should reduce to a minimum the metallic content of the tailings.

According to my invention I provide an 35 apparatus wherein a pulp containing the material to be separated is thoroughly aerated and wherein the bath is so agitated that substantially all the metallic particles are caused to rise to the surface of the bath 40 while the particles of gangue are allowed to settle. The apparatus is so constructed that the foam or froth containing the values is continuously removed while the settled gangue is also continuously withdrawn and 45 contains a minimum quantity of values. The apparatus is so constructed that the gangue is retreated, being taken from one compartment to the next and when finally discharged it has been separated from

practically all of the metallic values contained in the pulp. 50

The invention comprehends apparatus for aerating liquids in which a receptacle or tank is employed into which liquid pulp mingled with the necessary oil or other 55 froth-producing agents is introduced. Located at the bottom of this receptacle is a rotary head from which extends downwardly a short open-ended pipe which is in communication with the pulp in the bottom 60 of the tank. A conduit is also connected with this head and extends upwardly therefrom above the level of the pulp, the upper extremity of the pipe being open for the entrance of air. The lower pipe member is 65 in communication with the inner extremities of a number of passages formed in the head and whose outer extremities terminate at the periphery of the head while the upwardly extending conduit is in communication at its 70 lower extremity with a number of passages which also extend outwardly to the periphery of the head. As the head is rotated the centrifugal force draws pulp from the bottom of the tank and discharges it through 75 certain passages of the head to the periphery of the latter while the same force draws air downwardly through the upwardly extending conduit into the head and discharges it through other passages at the periphery of 80 the head.

In one form of the apparatus a series of agitation compartments is provided which communicate with a series of settling compartments and below each agitation compartment there is a chamber to which the pulp is delivered before passing upwards to the agitation compartment. Each agitation compartment contains means for distributing air within it and it also contains a distributor for the pulp which is closely associated with the air distributor. The agitated pulp passes from each agitation compartment to a settling compartment and a communication is provided between the 90 lower part of each settling compartment and a chamber below the next succeeding agitation compartment whereby the settled ma 95

terial may pass successively through the agitation and settling compartments of the apparatus. At the delivery end of the apparatus a chamber is provided to receive the 5 tailings and this chamber may be equipped with a float valve for regulating the discharge. The details of construction of this form of the apparatus will be hereinafter more fully described.

10 In another form of the apparatus some of the gangue is taken from each settling compartment and returned to the same agitation compartment from which it came, the gangue from each agitation compartment 15 which does not pass to the settling compartment being conveyed through a port to a chamber below the next agitation compartment from which it passes to a settling compartment. Other features of this form of 20 the apparatus will be described later on.

In the accompanying drawings:—

Figure 1 is a view in side elevation and partly in section showing one form of apparatus constructed in accordance with my 25 invention.

Figure 2 shows a transverse section thereof on the line 2—2 of Fig. 1.

Figure 3 shows a horizontal section on the line 3—3 of Fig. 1, some parts being 30 broken away in order to better illustrate other parts.

Figure 4 shows in vertical section the combined air and pulp distributors.

Figure 5 is a plan view of the combined 35 agitator and distributors with the air supply tube in section.

Figure 6 is a view similar to Fig. 1 of a modified form of the apparatus.

Figure 7 shows a transverse section on 40 the line 7—7 of Fig. 6.

Figure 8 shows a horizontal section of the modified form of apparatus shown in Fig. 6.

Figure 9 shows a vertical section of a 45 slightly modified form of distributor.

50 The vessel A is divided into a series of agitation compartments and a series of settling compartments. As shown in Figs. 1 and 2 the vessel has a flat horizontal bottom a with sides a' which incline upwardly and outwardly and on each side of the vessel there is an overflow launder a^2 provided with a discharge pipe a^3 . The ends of the vessel are closed by end-pieces a^x and a^{xx} as shown. Upright longitudinal partitions a^4 55 divide the vessel into three sections, the middle section being subdivided by transverse partitions a^5 into agitation compartments B' , B^2 , B^3 , B^4 . The two outer sections are divided by transverse partitions b 60 into a series of settling compartments C' , C^2 , C^3 , C^4 . I preferably employ two sets of settling compartments as shown but only one set need be used.

The agitation compartments are all arranged above a false bottom D and the

space between this false bottom and the bottom a of the vessel is divided by transverse partitions d into a series of chambers E' , E^2 , E^3 , E^4 , E^5 . The several compartments and chambers communicate with each other in the manner hereinafter described. 70

In each agitation compartment there is a combined agitator and distributor F, each of which comprises a vertically arranged tube f connected at its lower end with an air 75 distributor f' which communicates with the tube and which is arranged above a pulp distributor f^2 . The tubes and the distributors are rotated by gearing g operated by a power shaft G.

Various forms of distributors and agitators may be employed, but in Figs. 4 and 5 I have shown the preferred construction. As there illustrated two circular plates or discs h , h' carry between them blades h^2 80 disposed as shown in Fig. 5, and the construction is such that as the distributors are rotated air will be discharged by centrifugal force from the periphery of the distributor. The tubes f are all open, air enters at their

upper ends and passes down to the air distributors f' and is thrown centrifugally outwards into the agitation compartments. The pulp distributors f^2 are formed in a similar way, blades h^4 being mounted 95

between the plates h' and h^3 . These blades may be disposed in various ways, but the construction should be such that the pulp which enters the center of the distributor shall be thrown outwards by centrifugal 100 force. Preferably the upper disc h is perforated as shown so that air will not only pass outward from the periphery of the distributor but will also pass upwardly

therefrom and thus increase the distribution 105 of the air for agitation and flotation purposes.

The distributors of course operate to draw air and pulp to their centers as well as to discharge air and pulp from their peripheries. It will be observed that the distributor F is in the form of a rotary head or member and is provided with a set of passages extending from its central portion towards its periphery which communicate 110 with the hollow member or shaft f , which in turn communicates with the atmosphere above the liquid in the tank, and said head is provided with another set of similar passages having both ends of each passage in 115 communication with the liquid in the tank. The several passages above described are produced by the blades h^2 and h^4 between the upper and lower discs and the intermediate disc. 120

The pulp is mixed with oil or other froth-producing agent preferably before it is fed to the apparatus but it may be supplied in any suitable way.

The pulp may be fed to the tube f of the 125

first agitator through a supply conveyer α as indicated in Fig. 1. When the pulp is thus supplied it enters with the air and becomes, to some degree, mixed therewith before it passes out from the agitator or distributor F . Pulp may also be delivered through a supply pipe H which enters the first chamber E' in the series. Each chamber E' , E^2 , E^3 , E^4 communicates with the 5 agitation compartment above it through a tube I which, as shown in Fig. 1, has a threaded connection with the partition D and which enters the pulp distributor in said agitation compartment. The capacity of 10 each of said tubes may be regulated by an adjustable bolt J in an obvious manner. Each agitation compartment communicates with a corresponding settling compartment on each side of it through openings y disposed between slats or baffles y' . As the 15 pulp rises in the agitation compartments it passes through the openings between the slats and these slats or baffles serve to retard the upward air currents so that when the pulp passes to the settling chambers quiet 20 settling may be more efficiently accomplished. Each settling compartment or each pair of settling compartments communicates with a chamber below the next agitation 25 compartment in the series as indicated at c in Figs. 1, 2 and 3 of the drawings. The last chamber E^5 of the series communicates by means of an opening e with a chamber L for the tailings or gangue after the metallic 30 values have been separated. This chamber L is provided with a discharge opening e' provided with a valve e^2 controlled by a float e^3 in well known ways.

If it be necessary to maintain an even fluid 40 level in all the settling compartments, it can be accomplished by providing openings or communications between said compartments controlled by slides or valves N .

As before stated, the pulp may be fed to 45 the first tube f by means of a supply pipe α , or it may be fed to the first chamber E' by a pipe H . In fact pulp may be supplied simultaneously to the first agitation compartment from both of these sources. The 50 several agitators and distributors are rotated simultaneously and continuously. In the first compartment the pulp is distributed and thoroughly mixed with the air thrown out by the agitator. The agitated pulp 55 passes through the openings y into the settling chambers C' . The froth with the metallic values passes over into the launders a^2 while the settled material passes through the opening c to the chamber E^2 below the 60 second agitation compartment B^2 . In this compartment the settled pulp from the first compartment, deprived of some of its values, is thoroughly agitated and aerated and passes to the settling compartments on each 65 side of it, the froth rising and overflowing

into the launders a^2 and the settled material passing through the openings c to the chamber E^3 below the third agitation compartment. The material in like manner passes through the other compartments in 70 the series, the froth overflowing into the launders and the gangue passing to the chamber L . The froth may be conveyed away for further treatment. Preferably but not necessarily, the troughs or launders are 75 continuous and preferably each agitation compartment is provided with a settling compartment on each side of it, although obviously it is only necessary to provide each agitation compartment with a single 80 settling compartment.

By this apparatus a thorough commingling of the pulp with the air is accomplished in all of the compartments. Much of the metallic values is removed from the pulp in 85 the first compartment and as the material passes through the several compartments the remaining metallic values are gradually separated so that the gangue which reaches the chamber L is practically free from all 90 materials of value which it is desired to recover.

In Figs. 6 to 9 of the drawings I have shown some modifications. Much of the apparatus is similar to that before described 95 and the parts are similarly lettered. In this case, however, the bottom a of the vessel is preferably inclined. The agitators and distributors are of the same construction as those previously described but in this case 100 the tubes I are shown as being rigidly connected with the distributors and rotating with them. Instead of employing a continuous partition D , as shown in Fig. 1, a series of false bottoms o are used and the 105 tubes I extend through said false bottoms and are free to rotate therein. The settling compartments are similar to those before described and communicate with the agitation compartments in a similar way except 110 that each chamber below an agitation compartment communicates with the settling compartments associated therewith through openings n , that is to say, the settling compartments C' communicate with the chamber E' below the agitation compartment B' . The compartments C^2 communicate with the chamber E^2 below the agitation compartment B^2 and so on, so that in this way material which has passed from each agitation 115 compartment is returned thereto for re-treatment but each agitation compartment communicates with the chamber below the next agitation compartment through an opening r and it is through these openings 120 that the settled material passes through the apparatus to the discharge chamber L . The pulp may be fed to the tube f of the first agitator and it may be also fed to the first agitation compartment by a pipe H' which 125

communicates with the chamber E' in the manner indicated. The agitated pulp passes from the first agitation compartment B' to the settling compartments on each side of 5 it and is returned in the manner before described. Settled material in the first compartment B' passes through the port or opening α to the chamber E² below the second agitation compartment and in like manner 10 the material passes from an agitation compartment to a settling compartment throughout the series and from the several agitation compartments to chambers below the succeeding agitation compartments and 15 so on until the gangue or tailings finally reaches the chamber L from which it is discharged, while the froth containing values is received by the troughs or launders α^2 and conveyed away for further treatment. 20 It will, of course, be understood that any desired number of compartments may be employed for agitation, settling, etc. The specific number shown is not essential. The apparatus is self contained requiring no 25 auxiliary apparatus to supply air under pressure, the rotary agitators serving to induce or draw in air which is forcibly discharged into the agitation compartments where it mingles thoroughly with pulp 30 which is induced and distributed by the rotary pulp distributers associated with the rotary air distributers.

While I prefer to employ the chambers E', etc. below the agitation compartments it 35 is obvious that such chambers constitute part of the means for conveying the settled pulp from a settling compartment to the next agitation compartment in the series and that a more direct connection might be employed. 40 In case the pulp is fed to the first agitation compartment by way of the tube γ only, as indicated at α in Fig. 1, it will not be necessary to provide a pulp distributer in the first compartment as the pulp is distributed by the same apparatus which distributes the air. 45

This application is a division of my application for patent No. 107,434, filed July 3, 1916, in which I have shown an apparatus 50 for concentrating ores comprising a series of agitation compartments, each provided with means for distributing air and pulp therein, a series of settling compartments communicating with the agitation compartments, a pulp-receiving chamber below each agitation compartment, and means for conveying settled material from the lower portion of one settling compartment to the chamber below the next agitation compartment. I do not herein claim such subject matter as claims thereto are made in my application for patent No. 107,434, filed July 3, 1916.

I claim as my invention:

1. Aerating apparatus, including a tank, a

rotary member located therein and provided with a set of air passages extending from its central portion towards its periphery, and a hollow member through which said passages are in communication with the atmosphere 70 above the liquid which the tank is adapted to contain, and another set of similar liquid conducting passages having both ends of each passage in communication with the liquid in the tank. 75

2. Aerating apparatus, including a tank, a rotary member located therein and provided with an air passage extending from its central portion to its periphery, and a hollow member through which said passage 80 is in communication with the atmosphere above the liquid which the tank is adapted to contain, and another similar liquid conducting passage having both of its ends in communication with the liquid in the tank. 85

3. Aerating apparatus, including a tank, a rotary member located therein and provided with a plurality of independent air passages extending from its central portion to its periphery, and a hollow member 90 through which said passages are in communication with the atmosphere above the liquid, which the tank is adapted to contain, and another liquid conducting passage having both of its ends in communication with the 95 liquid in the tank, and means for rotating the said member at a speed to develop sufficient centrifugal force to overcome the pressure of the liquid in the tank, whereby air and liquid are taken into the said member 100 and discharged at its periphery.

4. Aerating apparatus, including a tank, a member mounted to rotate therein and composed of a head having a number of passages extending from its central portion outwardly 105 to its periphery, a tubular member connected with the head and extending above the liquid in the tank, said tubular member being open to the atmosphere at its upper extremity and in communication at its lower extremity 110 with the passages of the head, the rotary member having a depending conduit open at its lower extremity to allow the liquid of the tank to enter, the rotary member having a number of passages in communication with the said liquid-receiving conduit, said last named passages being open ended and extending from the central portion of the rotary member to its periphery. 115

5. A gas-diffusing device comprising a rotary head having a set of passages for gas extending outwardly away from the center towards the periphery of the head and having means for admitting air to the inner ends of said passages, a set of liquid-conducting passages also extending towards the periphery of the head and which are connected with means for admitting liquid to their inner ends. 120

6. Aerating apparatus comprising a tank 130

having an overflow at its upper portion and means for continuously supplying it with liquid, a vertical hollow shaft within the tank open to the atmosphere above the overflow portion of the tank, a rotary member within the tank provided with a horizontal passage extending from its central portion towards its periphery and through which air

5 passes outwards from the hollow shaft, and provided also with another horizontal passage through which liquid is conducted from the tank to the periphery of the rotary member.

In testimony whereof, I have hereunto subscribed my name.

FRANK GROCH.
